UNITED STATES PATENT OFFICE.

CHESTER W. CANINE, OF CINCINNATI, OHIO.

MARKING-MACHINE FOR LAUNDRY ARTICLES.

No. 927,487.

Specification of Letters Patent.

Patented July 13, 1909.

Application filed November 25, 1905. Serial No. 289,115.

To all whom it may concern:

Be it known that I, CHESTER W. CANINE, a citizen of the United States, residing in Cincinnati, county of Hamilton, and State of Ohio, have invented a certain new and useful Improvement in Marking-Machines for Laundry Articles, of which the following is a full, clear, and exact description, reference being had to the accompanying drawings, 10 forming part of this specification.

My invention relates to machines for marking laundry articles, whereby the type for printing any desired name or series of numbers of both name and numbers, together 15 may be set in operative position most expeditiously, and the invention consists of that certain novel construction and arrangements of parts to be hereinafter particularly pointed out and claimed.

20 In the drawings Figure 1 is a sectional side elevation taken just within the casing. Fig. 2 is a front elevation of the machine. Fig. 3 is a similar front elevation with the front casing and parts of the printing devices removed. Fig. 4 is a detail horizontal cross section, taken on the lines *a—a* of Fig. 1.

1 is the bottom plate, 2, 2 the side walls, and 3 the back wall of the casing for the working parts which parts are journaled and supported in the side standards 4, inside the casing.

5 is the front casing, which in its upper part 6 is semi-cylindrical in shape, and is provided with a series of slots 7 for the passage 35 of the operating handles of the mechanism.

Strung on the shaft 8, journaled across the machine in the side standards 4, 4 are a series of sector plates 9, provided with gear 40 teeth 10, and each sector plate meshes with the type teeth 11 of a corresponding series of type wheels 12, which are mounted on the shaft 13 secured across the frame. On the outside of the casing along side of the slots 7 45 the letters of the alphabet and numerals from 0 to 9 are indicated in vertical series 60, and each sector plate is provided with an arm 14, which extends up through its proper slot 7. For economy of space, the sector plates 50 and type wheels are mounted almost in contact with each other, and side extensions 15 are formed on the upper end of the sector plates, so that each arm 14 may be arranged in proper position to pass through its proper slot in the case. The arms 14 are united to 55 the respective extensions of the sector plates

by the screws 16 which take into block 61 riveted to the end of the arms, the arms being slotted at 62, so that their position can be properly adjusted, while a horizontal tongue 63 on each arm 14 takes into a corresponding groove in its respective block to prevent the arm from turning.

Mounted on each arm outside the casing is a toothed plate 17, which takes into notches 18, which are arranged opposite each letter and numeral as indicated on the casing lengthwise of the slots, and these plates are raised by the finger latch 64 to permit movement of the arms from one position to another. These finger latches 64 are pivoted at 19 to an extension 65 of the arm 14, and are connected with the plates 17 which slide on the arm by the links 20, while 21 is a coiled spring bearing between the plate 17 and the finger latch, so that when the latch is released the toothed plate will find a seat within the notches opposite the desired letter. By pressing the arm across and back of all of the latches all of the plates will be raised and 80 all of the arms may be brought down to the lowest position simultaneously.

The type for the letters and numerals are arranged on the periphery of the type wheels at the end of the teeth, and the parts are so 85 constructed that when the arm on any sector plate is brought down opposite any particular letter or numeral, the sector plate shall rotate its type wheel to bring the corresponding type into printing position at the opening 90 22 in the front casing.

In order to set the type wheels for the printing of any desired name, or series of numerals, the operator grasps the finger latch 64, raising the plate 17, and brings the arm 95 down opposite the particular letter desired, and this movement will set the type wheel in the proper position. It is not necessary to reset the sector plates, and type wheels for new names, but the arms can be moved directly to the new position. These arms can be operated very rapidly.

In order to guide the movement of the sector plates each plate is provided with a slot 23, which rides on the rod 24 supported across 105 the machine in the side standards 4, 4, while to properly separate the sector plates and prevent engagement with an adjoining type wheel this rod 24 is provided with a series of teeth 66, forming a comb for spacing the 110 plates, the rod being mounted with the comb teeth in horizontal position.

25 is the printing lever carrying the platen 26, and this lever is pivoted in the bottom of the case on the shaft 27, which carries an arm 28 connected by the link 29 to the arm 30 on the rock shaft 31. This rock shaft carries 5 also the segmental hook plate 32 pivoted at 33 on the end of the rock shaft arm 30, and connected at the rear by the coiled spring 34 with the nose 35 on the rock shaft 31. The 10 hook or shoulder 36 of the segmental plate 32 engages a roller pin 37, mounted in the arms 43 of a rock shaft 39, which rock shaft is provided with the arms 38 carrying the segment gears 40, which mesh with the teeth 41 on the 15 inner curved ends of the inking bar 42, which bars carry at their outer end the inking pad 44, which receives its ink from a pad 45 pivotally mounted in the casing, and provided with a projection 46 against which the 20 end of the inking bar bears to keep the two pads in close contact.

As the printing lever 25 is pushed by the handles 47 toward the machine, the rock shaft 31 is rocked, which in turn actuates the 25 segment gears 40 to rock or draw down the inking bar 42. The inking pad on the bar is pressed against the type, and the further movement of the hook plate 32 causes it to slip off of the roller pin 37, and the inking bar 30 is returned to its normal position by the coiled spring 48 attached between the upper end of one arm 38 and the casing. The movement of the segment rack 40 after the inking pad has been brought down over the 35 type exposed through the opening 22, draws the inking bar 42 inward to press the pad on the type, and causes the notch 49 on the inner end of the inking bars to engage the roller pins 50 on the standard, so that in the return movement the inking bar and the pad will be thrown forward before it can be returned to 40 its normal position to prevent the inking pad from rubbing upon and smearing the case upon its return movement.

45 The operation of the machine will be evident from the foregoing description. The operator first sets the type wheels for any name or series of numerals desired by bringing down the arms 14 on the sector plates opposite the proper letters or numerals. The goods to be marked are then placed over the platen 26 and the printing lever raised by the handles 47. This movement as heretofore described causes the inking pad to ink the 50 type, and the further movement inward of the printing lever presses the platen and goods against the type to imprint the desired name or numbers thereon.

Having thus described my invention, what 55 I claim as new, and desire to secure by Letters Patent, is:

1. In a marking machine for laundry articles in combination with a fixed case, a plurality of type wheels; each provided with a 60 series of type forming gear teeth with a shaft

mounted in fixed position in the case, upon which shaft the type wheels are strung, and a corresponding number of oscillating sector plates meshing therewith, each provided with an arm for operating said sector plates, 70 and a series of letters and numerals indicated on the casing in line with the throw of said arms, whereby the setting of the arms opposite the particular letters will bring a corresponding letter on the connecting type wheel 75 into printing position and a platen bearing pivoted lever for impressing the goods to be marked, on the selected type.

2. In a marking machine for laundry articles in combination with a fixed case, a plurality of type wheels, each provided with a series of type forming gear teeth with a shaft 80 mounted in fixed position in the case, upon which shaft the type wheels are strung, and a corresponding number of oscillating sector plates meshing therewith, each provided with an arm for operating said sector plates, 85 a cover plate with longitudinal slots therein, through which said arms extend, with a series of letters and numerals indicated on the casing opposite said slots, whereby the setting of the arms opposite any particular letter will bring a corresponding letter on the intermeshing type wheel to printing position and a platen bearing pivoted lever for impressing 90 the goods to be marked on the selected type.

3. In a marking machine for laundry articles, a plurality of type wheels, a shaft upon which said wheels are strung in contact with each other, a corresponding number of oscillating sector plates, a shaft upon which said plates are mounted, and a slot in each plate with a rod mounted in the casing passing through said slots to guide the plates, said rod carrying teeth to form a spacing bar for 100 spacing apart the sector plates, to compel engagement thereof each with its corresponding type wheel.

4. In a marking machine for laundry articles, a plurality of type wheels each provided 110 with a series of type with a shaft mounted in fixed position in the case, upon which shaft the type wheels are strung, and a corresponding number of oscillating sector plates in engagement with said type wheels, and each 115 provided with an arm for operating said sector plates, and a series of letters and numerals indicated on the casing in line with the throw of said arms, a platen bearing lever for impressing the goods to be marked on the 120 selected type, and an inking device for the type with connecting mechanism intermediate the lever and inking device whereby the initial movement of the lever will cause the ink to be spread over the selected type between each printing operation.

5. In a marking machine for laundry articles, a series of type wheels in close proximity to each other and a corresponding series of 125 movable plates, with side extensions on said 130

plates, blocks on the ends of said extensions, with arms attached thereto said arms and blocks being tongued and grooved to prevent turning.

5 6. In a marking machine for laundry articles, a series of type wheels in close proximity to each other and a corresponding series of movable plates, with side extensions on said plates, blocks on the ends of said extensions,

with arms attached thereto, said arms and 10 blocks being tongued and grooved to prevent turning, with slots on the arms through which they are secured to permit adjustment thereof.

CHESTER W. CANINE.
